CLAIM

The ornamental design for a watch with display, as shown and described.

DESCRIPTION

FIG. 1 is a front perspective view of a watch with display according to the present invention;

FIG. 2 is a rear perspective view of the watch with display;

FIG. 3 is a top view of the watch with display;

FIG. 4 is a front view of the watch with display;

FIG. 5 is a bottom view of the watch with display;

FIG. 6 is a rear view of the watch with display;

FIG. 7 is a left side view of the watch with display;

FIG. 8 is a right side view of the watch with display.

The broken lines shown in FIGS. 1 through 8 represent portions of the watch with display that form no part of the claimed design.

1 Claim, 4 Drawing Sheets
